LOUIS KOVACS, OF CHICAGO, ILLINOIS.

CUT-OUT SWITCH.

1,049,371.

Specification of Letters Patent.

Patented Jan. 7, 1913.

Application filed October 30, 1911. Serial No. 657,499.

To all whom it may concern:

Be it known that I, LOUIS KOVACS, a subject of the Emperor of Austria-Hungary, residing at Chicago, in the county of Cook and State of Illinois, have invented a new and useful Improvement in Cut-Out Switches, of which the following is a complete specification.

The main objects of this invention are to provide an improved cut-out switch; to provide an improved construction adapted to prevent a greater current passing through the wire attached to the fuse than that called for by the wire rating; to provide a cut-out switch in which it is impossible to connect a fuse for less current strength than the capacity or rating of the wire leading to the cut-out; and to provide a cheap, simple and durable device adapted to perform its work with great efficiency.

The invention consists of the matters hereinafter described in the specification and more fully pointed out and defined in the appended claims.

In the drawings: Figure 1 is a side elevation of a cut-out and fuse for a cut-out switch embodied in this invention, and showing one means for securing the cut-out socket to the fuse plug. Fig. 2 is a plan view of the cut-out switch, with one of the cut-outs and fuses in longitudinal section. Fig. 3 is a longitudinal section of the switch taken at right angles to the section shown in Fig. 2. Fig. 4 is a view of the cut-out partly in section and partly in side elevation, with a contact for a given amperage. Fig. 5 is a longitudinal section of the fuse plug with a contact of less amperage than that of the cut-out shown in Fig. 4 and showing that it is impossible to connect the two contacts. Fig. 6 is a longitudinal section of the cut-out showing the contact marked to indicate the different lengths of the contact required to carry various numbers of amperes within a given wire rating. Fig. 7 is a similar view of the fuse plug showing the contact marked to indicate different lengths of contact to correspond with that of the cut-out. Fig. 8 is an enlarged side elevation partly in section of the switch blade. Fig. 9 is a top plan view of the outer insulating piece or body for the fuse plug. Fig. 10 is a central section of said insulating

piece. Fig. 11 is a bottom plan view of the same. Fig. 12 is a top plan view of the inner insulating piece or body for the fuse plug. Fig. 13 is a central section of the inner insulating piece. Fig. 14 is a bottom plan view of the inner insulating piece. Fig. 15 is a plan view of the binding plate for the fuse contact. Fig. 16 is a side elevation of the fuse contact with the binding plate in section and illustrating the different lengths of contact required for various numbers of amperes within a given wire rating.

In the drawings: The cut-out 1 comprises a cup shaped shell or socket 2, of brass or copper, which is provided on its bottom with an ear 3 adapted to be hinged to ears 4 on a switch base 5. Within the shell 2, and secured to the bottom axially thereof, is the contact guide socket 6 of copper. An inverted cup shaped contact support 7 is carried in the inner portion of the shell 2 and is provided in its sides with guide grooves 8 into which project guide screws 9, carried in the walls of the shell 2 and which permit the contact support to move longitudinally of the shell but hold it from rotation therein. A coiled spring 10 bears at one end on the bottom of the shell 2 and at its other end against the bottom of the contact support 7 and normally acts to hold said support at the outward limit of its movement in the shell. The cut-out contact 11 has a reduced inner end which extends through an aperture in the support and is threaded to receive the binding nuts 12 on the inner side of the support which holds said contact in place, while the extreme inner end of the contact extends into the guide socket 6 and forms an electrical connection therewith.

The fuse plug comprises an outer insulating piece or body 13 and an inner insulating piece or body 14, both of which are formed of porcelain, and are connected together by a brass sleeve 15 which is secured to the piece 13 by means of screws 16 which extend into cavities 17 in the walls of said piece which carry nuts 18 and are filled with a special heat resisting filling of any desired character. The sleeve 15 is secured to the piece 14 by means of screws 16a engaging nuts in cavities 19 in said piece. An outer sleeve 20, of fiber, incloses the sleeve 15 and the pieces 13 and 14, and is

secured to the piece 14 by means of screws 21 engaging nuts 22 in cavities 23 in the bottom of the piece 14. The lower end 24 of the piece 14 is reduced in size, and a copper cap 25, having an annular portion through which said reduced portion extends, fits over the end of the sleeve 20 and is secured in place by means of the screws 21 and by screws 26 engaging nuts 27 in cavities 28 in the sides of the piece 14.

10 A copper binding plate 29 is countersunk in a cavity or seat 30 in the inner end of the insulating piece 14, and is secured to said piece by means of screws 31 engaging nuts 32 in cavities 33 in said piece. The fuse contact 33 has a reduced, threaded inner end 34 which extends through said plate 29 and has binding nuts 35 thereon, between which one end of the fuse 36 is secured.

15 The switch blade 37, of copper, has a cylindrical portion 38 which extends through the aperture 39 in the insulating piece 13, and is provided with a flange 40 which seats in a seat 41 in the outer end of the piece 13. On the inner end of the portion 38 are binding nuts 42 which hold the blade in place. The portion 38 is provided with a bore 43 through which the end of the fuse 36 extends and is secured between the flange 40 and a copper cap 44 covering the outer end of the sleeve 20 and the insulating piece 13. Lining the cavity formed by the sleeve 15 and the insulating pieces is a layer 45 of asbestos.

20 The cut-out may be connected with the fuse plug in any desired manner. As shown in Figs. 1, 4 and 5, the cut-out shell 2 has curved notches 46 in its sides opening through the edge, and the plug has screws 47 adapted to engage in said notches. In Figs. 2, 3, 6 and 7, the cap has threaded engagement in the shell 2. A wire of a given size is rated to carry a current strength ranging between certain numbers of amperes. For a rating of a given size of wire, the cut-out contact 11 and the fuse contact 33 will be of the same diameter but will correspondingly increase and decrease in length as the number of amperes for which 25 the particular cut-out switch is to be employed. For instance, if a given size of wire is rated to carry from 195 to 245 amperes, and the cut-out switch is to carry 195 amperes only, the cut-out contact 11 will be 30 of a length to extend from the support 7 to the line *a*, Fig. 6, and the fuse contact 33 will be full length, as shown in Fig. 7. If the number of amperes is to be increased by 10 up to the maximum 245, the contact 11 will be increased in length corresponding to the lines *b*, *c*, *d*, *e* and *f*, and the contact 33 will correspondingly decrease in length as indicated by similar lines thereon.

35 The current which enters the switch through the blade 37 will pass, successively, through fuse 36 and contact members 33 and 11, and thence out through ear 3. If for any reason either of the contact members 33 or 11 be too short, said members will not touch, and the current will not pass through the switch. On the other hand, if either of said members 33 or 11 be too long, the cartridge or shell, shown in Figs. 5 and 7, (which cartridge contains the fuse 36 and the member 33) will not fit within the shell 70 or socket shown in Figs. 4 and 6, and the device cannot be assembled, because in order to permit assembling the device, the sum of the lengths of contact members 33 and 11 must not exceed the distance between the fixed plate 29 and the cup 7. The contact members 33 and 11, therefore, are made of certain definite lengths to accord with the rated amperage of the line wire. One of said plugs increases in length as the number of amperes increases; whereas, the other plug decreases in length as the amperage increases. For example, if the contact member 33 be made relatively long for a low amperage, the plug 11 must be made relatively 35 short for the same amperage, and, if the contact member 33 be relatively short as for a high amperage, the member 11 must be relatively long. The members 33 and 11 are not designed to blow out or melt but they either 40 prevent assembling the device or they cause a break in the circuit if the device is assembled, unless said respective members 33 and 11 are each of the right length to co-act with each other, and to complete the circuit by 45 exactly bridging the distance between members 29 and 7.

50 Since the cartridges shown in Figs. 5 and 7, and the sockets shown in Figs. 4 and 6, are each put together at the factory, it is very 55 difficult for an ignorant, careless, or negligent workman to remove or insert a new member 33 or 11 on the job. At the factory each cartridge and each base will be provided with a contact member 33 or 11 of 60 exactly the right length for the amperage connection with which each cartridge or base is to be used. The workman on the job, therefore, must use a cartridge and a base adapted to co-act with each other, and he 65 cannot, merely, to save himself inconvenience or delay, make any substitution, but must use a cartridge and a base which are mated for each other. He cannot, for example, use a 250 ampere cartridge with a 110 70 125 ampere base, because in such event he could not secure the cartridge within the base. Neither can the workman use a 125 ampere cartridge with a 250 ampere base because, in such event, the members 33 and 11 115 would not touch and the circuit would not be complete.

75 It will be noted that this structure includes in a single unitary switch both a safety plug and a safety fuse. Each safety 80 85 90 95 100 105 110 115 120 125 130

plug is adapted to be used for a single rated current strength only, but it is impossible to use a safety plug designed for a given amperage in conjunction with a fuse designed for another amperage.

5 I claim as my invention:

1. A device of the character described, comprising a cut-out shell, a yielding contact support in the shell, a cut-out contact 10 mounted upon said support, a fuse plug, a fuse contact in the fuse plug, a fuse connected with the fuse contact, and a switch blade connected with the fuse, the length of each of said contacts being proportional to the 15 amperage at which said fuse is adapted to blow out.

2. A device of the character described, comprising a cut-out shell, a movable contact support therein, resilient means normally to hold the contact support at the outer limit of its movement, a cut-out contact mounted upon said support, a fuse plug, a fuse contact carried in the plug and adapted to engage the cut-out contact, a fuse connected with the fuse contact, and a switch blade connected with the fuse.

3. A device of the character described, comprising a cut-out and a fuse, co-acting contact members in the cut-out and in the 30 fuse, the length of each of said members being determined by the amperage, a switch

blade, and a fuse intermediate said blade and one of said contacts.

4. A device of the character described comprising a cut-out shell in hinged relation 35 to the switch base, a cartridge adapted to co-act with said shell, a switch-blade connected to said cartridge, co-acting contact members in said shell and in said plug, and a fuse intermediate one of said contact members and the blade, the length of each of said contact members being proportioned to the amperage which can be carried by said fuse.

5. In a device of the character described, the combination of a cut-out shell adapted to be hinged to a switch base, a cartridge adapted to be connected therewith, a switch-blade connected to said cartridge, co-acting contact members in said shell and in said cartridge, a fuse intermediate said blade and one of said contact members, conducting members fixed in said cartridge and in said shell, the sum of the lengths of said co-acting contact members being sufficient to bridge 55 the space between said fixed conductor members.
